DESIGN FOR A NAIL SET

Walter Bedell, Glen Cove, N. Y.

Application January 21, 1944, Serial No. 112,288

Term of patent 14 years

To all whom it may concern:

Be it known that I, Walter Bedell, a citizen of the United States and resident of Glen Cove, in the county of Nassau, in the State of New York, have invented a new, original, and ornamental Design for a Nail Set, of which the following is a specification, reference being had to the accompanying drawing, forming a part thereof.

Fig. 1 is a front elevational view of a nail set, showing my design; Fig. 2 is a plan view of the same; and Fig. 3 is a side elevational view of the same.

I claim:

The ornamental design for a nail set, as shown.

WALTER BEDELL.
